ASH POT

Teikichi Go and Kenichi Kojima, Azabu-Ku,
Tokyo, and Saburo Sugihara, Higashi Katsu-
shika-Gun, Chiba-Ken, Japan

Application October 18, 1934, Serial No. 748,814
In Japan November 20, 1933

1 Claim. (Cl. 131—51)

This invention relates to an improved ash-pot made of metal plate, which consists in attaching by a hinge a semi-circular lid and the lower portion of a pail-shaped front plate to the upper and lower portions of a back plate having bent edges at both sides respectively, said lid having a semi-cylindrical edge bent downward; and providing at the bottom of said lid an ash receiver formed at a part of a spherical surface; making outlet for ashes at the bottom of said ash receiver; pivoting by means of a pin to the outer surface of the upper portion of the ash receiver a revolving shutter fitted closely to its bottom, projecting a knob at one end of the shutter from a hole cut on the lid and fastening to the pin a spring with its ends secured to the shutter and the back of the lid respectively. The object thereof is to obtain an ash-pot easily attachable to any desired walls of automobiles and other kinds of vehicles and rooms which can prevent room air from being spoiled by tobacco smoke and smell by closing its lid perfectly when an unextinguished cigarette stub is put in it and which also enables ashes to be removed easily by unfastening its front plate.

Referring to the accompanying drawing, which shows an example of carrying out this invention into practice,

Fig. 1 is a plan;

Fig. 2, an elevation;

Fig. 3, a side elevation partly in section at the line A—B of Fig. 1 and

Fig. 4, the lid and front plate in a developed condition.

In the drawing, 1 is a main body made of metal plate, consisting in combination of a back plate 2 having bent edges at both sides and a pail-shaped front plate 3. 4 is a lid fitted to the main body; 5, a hinge for connecting the pail-shaped front plate and the semi-circular lid 4 to the lower and upper parts of the back plate respectively; 6, an indentation for attaching together the back plate 2, front plate 3 and lid 4 when they are folded one upon another at the hinge;

and 7, an ash receiver having its bottom formed at a part of a spherical surface. 8 is an ash outlet at the bottom of the ash-receiver; and 9, a revolving semi-circular shutter having both ends attached to the outer surface of the upper portion of the ash receiver 7 and also having a knob at one end which projects from a hole cut at the upper part of the lid, the whole having an arc-shape so as to be fitted to the spherical surface of the ash receiver 7. 10 is pin for supporting 10 the revolving shutter; 11, a spring with its ends secured to the shutter 9 and the back of the lid 4 respectively; and 12, a hole through which the back plate 2 is screwed fixedly to the side wall. According to this invention, a receptacle is formed 15 by folding one upon the other the back plate 2 and pail-shaped front plate connected together by a hinge, fixing them together by engagement with an indentation, covering them with the lid 4 connected therewith by a hinge and then connecting all together by engagement with the indentation. The outlet is opened by pressing the shutter 9 with a finger to drop ashes into the main body and the surface of the shutter 9 is kept clean by scratching with the back of the 20 ash receiver 7. By a spring the shutter is restored to the original position and at the same time is kept from shaking.

What is claimed is,

An ash tray comprising a back plate having 30 bent edges, a semi-circular lid pivotally attached to the upper end of the back plate, said lid having a semi-cylindrical edge and a downwardly inclined chute positioned inwardly of the edge, a pivotally mounted, spring operated closure forming 35 a continuation of the chute in its closed or normal position and having a knob projecting through said lid, and a front plate pivotally connected to the lower end of said back plate and adapted to be engaged beneath the edge of said 40 lid.
